UNITED STATES PATENT OFFICE.

HYMAN ELI GOLDBERG, (NOW BY JUDICIAL CHANGE OF NAME HYMAN GOLBERG,) OF CHICAGO, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

CALCULATING MACHINE.

1,404,954.

Specification of Letters Patent. Patented Jan. 31, 1922.

Application filed September 16, 1912, Serial No. 720,612. Renewed December 8, 1921. Serial No. 521,035.

To all whom it may concern:

Be it known that I, HYMAN ELI GOLDBERG, of Chicago, county of Cook, and State of Illinois, have invented certain new and useful Improvements in Calculating Machines, of which the following is a specification.

My invention is an adding and subtracting machine. It is intended primarily as an attachment to a typewriter but may of course be used independently thereof. The purpose of this invention is the construction of a machine which is compact, reliable, and which requires but little force to operate it.

The invention is illustrated by the accompanying drawings, forming part of the application.

Referring to the drawings,

Figure 1 is a front elevation of the calculating attachment.

Figure 2 is a sectional elevation thereof.

Figure 3 shows a carrying gear co-operating with the carrying pinion.

Figures 4, 5, 6, 7, 8 and 9 are sections of the cycle shaft showing the arrangement of the various operating cams thereon.

Figure 10 is a rear elevation, and:

Figure 11 is a section, along the line 11—11 of Figure 10, showing the action of the cramp room mechanism.

The calculating machine may be imagined to be mounted upon a Remington visible typewriter. Therefore there are supposed to be present all the parts usually present in such a typewriter, inclusive of framework, numeral keys and carriage. In the drawings such portions of the framework as are represented have attributed to them the symbol 1. The numeral keys have the symbol 2; the carriage has the symbol 3.

Mounted upon the typewriter framework 1 is the adding machine framework 4. Connected to the carriage 3 of the typewriter is the totalizer bar 5, which thus travels with the carriage during the letter space advance thereof.

Each of the numeral keys 2 of the typewriter has connected thereto a link 6. The upper end of said link is connected to the back end of a lever 7, fulcrumed on a pivot 8, and provided with a stud 9 at the front end. The several levers 7 are not parallelly placed nor are they of equal lengths. As is best shown in Fig. 1, they are placed

at different angles and are of unequal lengths measured from right to left, but they are of equal lengths measured from front to back. Assuming therefore that the movement of the several numeral keys is constant in amount the result is that the movement of the various studs 9 is also constant in amount. But because of the mechanism described the several studs 9 are no longer scattered over a wide space, but are concentrated into a narrow space. This is the main function of the mechanism composed of parts 6, 7, and 8. Each stud 9 is embraced within a slot 10 formed on the bottom of a vertical raisable plate 11. Each plate 11 is suitably guided in the framework 4 and is provided with acting points 12, 13, 14, 15 and 16. Parts such as those numbered 2, 6, 7 and 11, may be termed "digital members," as there is one of them identified with each of the digits 2, 75 3, etc.

The acting point 12 is a projection which cooperates with a cramp-room mechanism composed of a plurality of swingers 17. Each swinger is fulcrumed in the framework at 18, and is provided at the top with a cramp-piece 19. The total width of all of the cramp-pieces 19 is somewhat less than the room allowed therefor in the framing. This permits the intrusion of the projection 12 between its two adjacent cramp-pieces 19, but does not permit the intrusion of two plates simultaneously. This is therefore a single key mechanism.

The acting point 14 of the plate 11 cooperates with a universal crossbar 20, extending horizontally from right to left. It forms the bottom member of a bail whose side members 21 are linked at their upper ends to crank-pins 22 rigidly fastened to a cycle shaft 23 mounted in the framing. The depressing of any of the keys 2, and the subsequent release thereof, first raises and then lowers the projection 14 on the plate 11, and thus also the bar 20, and thus causes the cycle shaft 23 to perform a complete revolution. The difficulty of the dead points has been overcome by the introduction of the dead point mechanism, which will now be described.

It is well known that at a dead point the pressure exercised by the link 21 upon crank-piece 22 is directly radial from the center of

- the cycle shaft 23. The latter thus has no tendency to rotate in either direction. If however the cycle shaft 23 when in such dead point position, be given a bias to rotate in its proper direction, then no such dead point will occur. Such a bias is given to said cycle shaft by means of the cam 24 rigidly mounted thereon, a cooperating lever 25 fulcrumed upon a lever shaft 26, and a spring 27. The parts are so dimensioned that during the part of the cycle when the link 21 is effective in rotating the shaft 23, the cam 24 puts energy into the spring 27. Just prior to the reaching of the dead point, the cam 24 brings its cutaway portion under its cooperating lever and the energy stored up in the spring 27 is returned and is effective in rotating the cycle shaft 23 over the dead center.
- It is desirable in a calculating machine that a calculation once initiated shall be finished. To help accomplish this purpose the cycle shaft 23 has been provided with a ratchet 28, cooperating with a pawl 29 fulcrumed on shaft 26, and provided with a tension spring 30. The cycle shaft can therefore rotate in only one direction and should the universal bar 20 be somewhat raised by the depressing of any of the numeral keys, then the universal bar will not be able to resume its normal position unless it first completely raises and then comes down again, because of a complete revolution of the cycle shaft.
- The above mechanism thus compels a complete cycle of movement of the universal bar 20 but does not compel a complete cycle of movement of the numeral key 2 which originated the movement. But mechanism for this purpose is present. It is a lever 31 fulcrumed at the acting point 13, previously mentioned. The lever is provided with three acting points, 32, 33 and 34. The points 32 and 33 cooperate respectively with a piece 45 of the framing provided with two acting points, 35 and 36. When the plate 11 is in its normal or lower position, then the parts are as shown in Fig. 2, namely 32 is below and somewhat to the front of 35, and 33 is below and somewhat to the back of 36. As soon as the plate 11 commences to rise the presence of 35 causes 32 to move toward the back while 33 swings to the front just over 36. Upon the further rise of the plate 11, 32 continues to be in contact with its cooperating part and the lever 31 thus remains in its operated position. The swing of the lever about its fulcrum has the effect of swinging hook 34 to the front. Said hook thus engages the top of the universal bar 20, and remains so engaged for the rest of the rise of the plate 11, and does not disengage until said plate has resumed its normal lower position. Since the initiating of a cycle of the universal bar 20 will not permit it to re-
- turn until said cycle has been completely moved through, and since by the mechanism just described the initiating of a cycle of a key lever locks it to said universal bar and retains said lock through said cycle until the completion thereof, it is evident that any key lever is also compelled to finish its cycle once it has been initiated.
- The digit mechanism of this machine will now be described. It is composed of a set of digit pins 40 and cooperating mechanism. The depressing of any numeral key protrudes its own digit pin to be further operated upon. Each digit pin 40 is supported at its front in the framing and at its back is pivoted to the upper portion of a lever 41. All the levers 41 are fulcrumed upon a shaft 42. Each lever 41 is provided with two acting points 43 and 44, cooperating respectively with the bevels 15 and 16, previously mentioned as being part of the plate 11. An examination of Fig. 2 shows that the raising of the plate causes the protrusion of digit pin 40 which protrusion lasts through the whole cycle of upward and downward movement of the plate and that the digit pin is not withdrawn to its normal position until the plate has again reached its normal position.
- The several pins 40 are arranged in two circular arcs as best seen in Fig. 1. The reason for the duplication of the arc is to thus obtain more room for the parts.
- Cooperating with the digit pins 40 is a scissor-like arrangement composed of two blades 45 and 46 both pivoted upon a fulcrum 47. The blade 45 is provided with a pin 48 and the blade 46 with a pin 49. The pins 48 and 49 are embraced in slots formed in a tiltable piece 50, fulcrumed at its center upon a stud 51. The stud 51 may be vertically raised from its normal lower position, shown in Fig. 1, until it becomes concentric with the fulcrum 47 of the two blades. The slots embracing the pins 48 and 49 and the fulcrum 51 are collinear. The bringing of the fulcrum 51 into coincidence with the fulcrum 47 thus necessarily brings the pins 48 and 49 into collinearity with the fulcrum 47. The angle having its vertex at 51 and whose two sides extend through the centers of the pins 48 and 49, thus becomes a constant angle, in this particular case, a straight angle. The relative position of the blades 45 and 46 to each other thus becomes constant although their absolute position angularly about the fulcrum 47 is undetermined as all three pieces, 45, 46 and the tiltable piece 50, can turn as a totality upon the then coincident fulcrums 51 and 47. But the angular position of this totality is determined by providing the blades 45 and 46 each with a half hole. The parts are so dimensioned that the operated position of the piece 50 causes the bringing together of

the two half holes to form one complete hole. Should there be nothing in said hole when thus completed then the angular position of the two blades would still be undetermined. But if previous to the closing of the two blades there be intruded in the pathway of the two half holes a digit pin 40, then the blades cannot pass said pin and as the two half holes close together to form 10 the one hole, and as the pin just fills said hole, then necessarily the blades must close on said pin and the angular position of the blades is therefore determined by the location of the pin upon which it closes.

15 Fig. 1 shows that the several digit pins are located so that the distance from one to the next adjacent forms a constant angle about the fulcrum 47. It is therefore evident that by the protrusion into the path- 20 way of the blades 45 and 46 of the proper digit pin and the subsequent raising of the piece 50, the blade 45 may be given a movement of 0, 1, 2, 3, etc., increments. The blade 45 has formed rigidly therewith a 25 gear 52 which also will thus be given a digital movement corresponding to the particular numeral key operated.

The raising of the fulcrum stud 51 from its normal lower position to its upper position is accomplished by means of a link 53, 30 a lever 54, and cams 55 and 56. The cams are mounted upon the cycle shaft 23 and the lever is mounted upon the lever shaft 26. Two cams are used instead of one in order 35 to make the movement of the lever 54 completely positive. The lowering of the tilt-able piece 50 to its normal position causes the opening of the two blades. Each blade however is located in a definite position by

40 the encountering of a fixed pin 40. The gear 52 cooperates with a pinion 57 mounted upon a shaft 58 extending horizontally from front to back. The shaft is provided with two bevel gears, 59 at the front, and 60 at the back. Both gears can 45 cooperate; but only one at a time, with two other bevel gears 61 and 62. 61 is rigid with a shaft 63 rotatable in a shiftable frame 77 and provided with a gear 64 rigid therewith.

50 Similarly the bevel gear 62 is rigid with a shaft 65 provided with a gear 66. The gear 64 meshes with a master wheel 67 and the gear 66 meshes with a master or totalizer-operating wheel 68. Both master wheels are 55 rotatably mounted upon a shaft 69 extending horizontally from right to left and supported in the shiftable frame. Rotatably mounted upon the shaft 69 to the left of each master wheel is a set of transfer pin- 60 ions 70.

The master wheels and transfer pinions cooperate with carrying pinions 71 rotatably mounted upon a horizontal shaft 72, in the totalizer framework 73. Each carrying pin- 65 ion 71 gears with an idle gear 74 which in

its turn gears with a numeral wheel 75 provided with the digits, 0, 1, 2, 3, etc. The totalizer cover is provided with a slot 76 through which the proper ones of said digits can be read.

The particular construction of the carrying pinions 71 and of the transfer pinions 70, is not a part of this invention and therefore will not be described.

70 The shafts 65 and 66 and the shafts 58 and 59 are all mounted in one framing 77 which is capable of being lifted in the framing of the calculating machine. This is accomplished through the intermediation of links 78, levers 79 and cams 80 and 81. The 75 cams are so shaped that upon the rotation of the shaft 23, first the framing 77 is raised until the master wheels and the pinions engage the totalizer carrying pinions; simultaneously the gear 57 engages the gear 52. 80 The frame then remains in its lifted position while the further rotation of the cycle shaft causes the digital movement of the gear 57, thus also of the master wheels, and also of the totalizer gears. Subsequent to 85 the cessation of this digital movement the frame is lowered to unmesh all the gears meshed by its raising. Then the gear 52 is brought back to its normal position by the lowering to its normal position of the tilt-able piece 50. 90

95 Each totalizer is provided with a locking bar 82, fulcrumed in the walls thereof at 83 and provided with a spring 84 tending to hold the gears locked. To similarly hold the master wheels 67 and 68 and their associated transfer pinions 70, locked, the framing 77 is provided with a number of sets of locking bars, 85, fulcrumed on said raisable 100 framing at 86. While theoretically one locking bar 85 for each master wheel and its associated set of transfer pinions is sufficient, in practice it is found convenient to subdivide this theoretical single locking bar 105 85 into an actual plurality of locking bars. Each locking bar is provided with a link 87 and a lever 88 which cooperates with two cams 89 and 90, upon the cycle shaft. The cams are so shaped that their levers all open 110 their locking bars simultaneously, but close their locking bars successively. The locking bar at the right closes first, the one adjacent to it at the left, next, etc. This overcomes the inaccuracy of movement in the various 115 totalizer carrying pinions and transfer pinions as they are alined successively going from right to left.

120 The action of the cams controlling the locking bars 85 may be described in greater detail in connection with Figure 8, in which figure a single pair of cams 89 and 90 are shown. It will be remembered that these cams 89 and 90 are rigid on the cycle shaft 23, and that said shaft makes one complete 130

revolution in a counter clockwise direction each time a numeral key is operated. The lever 88 has mounted thereon the two rollers 100 and 101, which co-operate with the cams 89 and 90 respectively.

Reference to cam 89 will show that it is provided with a lifting surface 104 and a drop 102. Reference to cam 90 will show that it is provided with a drop 105 which 10 co-operates with the roller 101 simultaneously with the action of the surface 104 on the roller 100, and a lifting surface 103 which cooperates with the roller 101 simultaneously with the drop 102 on cam 89, co-15 operating with the roller 100. Therefore each revolution of the cycle shaft will first rock the lever 88 in a clockwise direction, and then restore the lever 88 to its original position.

20 The time during which the lever 88 is in its displaced position is of course determined by the angle between the surfaces 104 and 102. Assuming that the pair of cams shown in Figure 8 are those which 25 operate the locking bar 85 immediately to the left of the master wheel, the next pair of cams 89 and 90 operating the next lever 88 to the left would have their surfaces 104 and 105 in line with the surfaces 104 and 30 105 of the pair of cams shown in Figure 8. However, the surfaces 102 and 103 would be displaced in a clockwise direction so as to make the angle between the surface 104 and 102 of said higher order cams greater 35 than that shown in the cams illustrated in Figure 8. A cam of still higher order would have the angle 104—23—102 still greater, so that the rotation of the cycle shaft 23 would result first in all the levers 88 being rotated 40 in a clockwise direction simultaneously, and then in the restoration of these levers 88 one after the other, beginning with the lever immediately to the left of the master wheel.

It is well-known that the spiral occurring 45 when the totalizer carries through all its orders can be corrected by first correcting the error of the wheel immediately adjacent to the master wheel, and then by correcting the error of wheels in higher order. It is 50 evident that with the arrangement of cams as above described this result will be obtained.

The link 87 has been introduced to allow the raising of the locking bar 85. Such 55 raising occurs because it is mounted in the framing 77.

The operation of the parts is as follows: First the framing 77 is raised to engage the 60 totalizer; then the locking bars are opened, the locking bar 85 opening the locking bar 82; then the digital movement occurs; then the locking bars are closed; then the framing 77 is lowered; and finally the digitizing gear 52 is brought back to its normal position.

Attention is called to the fact that the left side wall of the totalizer is provided with downhanging teeth in alinement with the teeth of the carrying gears in their normal position. When the framework 77 is 70 raised and the master wheel and the transfer pinions engage the totalizer gears, then the transfer pinion immediately underneath the left side wall of the totalizer engages the latter and is thus prevented from rotating. 75 All the transfer gears to the right thereof are each engaged with the totalizer gears and are thus completely under control. All the transfer gears to the left thereof have no tendency to rotate as any such tendency 80 would be imparted thereto only by friction from those to the right, and the rightmost of these totalizer-gear-noncontrolled-pinions is now held locked.

In some of the claims of this case I have 85 used the expression "constant aggregate motion linkage." By this, I mean a mechanism having three points of freedom, and so constructed that a determined motion being given to one of these points, there results 90 motion of the second and third points, and the sum of the motions of the second and third points is a constant. A linkage of this kind is admirably adapted for transforming a constant motion of the source into a differentiated movement of one of the points of freedom, and this differential motion may be had without the use of springs since it is only necessary to arrange the second and third points that their motions will be towards 100 each other and interpose an immovable piece between them. This linkage may be arranged in a variety of ways. I have disclosed one convenient form in this specification. Another example would be an epicyclic gear 105 movement more commonly known as a differential gear. It will be remembered that if one gives a certain motion to the center member of a differential the resulting motion may occur all on one side, or part on one side 110 and part on the other side, but in any event the sum of the resulting motions of the sides will be a constant. Another example of a link motion of this kind is given in my co-pending application, Serial Number 697,704, 115 filed May 16th, 1912.

The use of a linkage of this kind in a calculating machine for producing differential motion of the master mechanism offers peculiar advantages since such differential motion may be produced without springs of any kind. Each key has a member which may be thrust in the path of the linkage, and a universal member moved by any of the digit keys will close the linkage by such protruded 125 piece. I believe I am the first to show a linkage of this kind in combination with the master mechanism, and wish to cover same broadly.

Many changes may be made in the precise 120 position.

form and construction of the device herein shown without departing from the spirit of my invention.

I claim—

1. In a calculating machine, the combination of a set of reciprocatable keys, a cycle shaft rotatable always in the same direction, and a mechanism positively linked to said cycle shaft and controlled by said numeral keys for moving said cycle shaft through a complete cycle for the operation of each numeral key, the power to rotate said cycle shaft being supplied by said numeral key. 75
2. In a calculating machine, the combination of a set of reciprocatable digital members, a universal member adapted to be operated by any of said digital members, a cycle body rotatable always in the same direction, and means positively linked to said cycle body to operate the same by means of said universal member, whereby a reciprocation of any of said digital members results in said cycle body being positively driven through a complete cycle. 80
3. In a calculating machine, the combination of a set of reciprocatable digital members, a universal member adapted to be reciprocated by any of said digital members, a cycle body rotatable always in the same direction, and means positively connected to said cycle body and adapted to be acted on by said universal member to move said cycle body through a complete cycle corresponding to a single reciprocation of said universal member. 85
4. In a calculating machine, the combination of a set of digit keys, a reciprocatable universal member, means to reciprocate said universal member upon actuation of any of said digit keys, a cycle body, and means at all times positively connected to said cycle body to move said body through a complete revolution upon the reciprocation of said universal member. 90
5. In a calculating machine the combination of: a set of reciprocatable digital members; a reciprocatable universal member; a cycle body adapted to be rotated through a complete revolution by the reciprocation of the reciprocatable universal member; link mechanism connecting the reciprocatable universal member and the cycle body to produce a rotation of the latter, and mechanism for carrying the cycle body over its dead point positions. 95
6. In a calculating machine the combination of: a set of reciprocatable digital members; a reciprocatable universal member; a cycle body adapted to rotate in one direction; a link connecting the universal member and the cycle body to thus produce the rotation of the latter by the reciprocation of the former; and dead point mechanism for storing up energy during the effective portion of the movement of the link and for releasing the stored up energy when the link has reached the dead point position. 100
7. In a calculating machine the combination of: a set of reciprocatable digital members; a universal member reciprocatable by any of said digital members; hook mechanism for locking the universal member and the reciprocatable digital members together; and cam mechanism for operating the hook mechanism. 105
8. In a calculating machine the combination of: a set of digital pins; a constant aggregate movement mechanism adapted to cooperate with any of said pins to be located thereby; and a master wheel operated by the mechanism. 110
9. In a calculating machine the combination of: a set of reciprocatable digital members; a set of digital pins, one for each member; and cam mechanism connecting the reciprocatable digital member and the digital pin. 115
10. In a calculating machine the combination of: a set of digital pins; a constant aggregate movement mechanism composed of; a member rotatable about a fulcrum; another member rotatable about the same fulcrum; and mechanism for bringing said members into a constant position relatively to each other. 120
11. In a calculating machine the combination of: a set of digital pins; a constant aggregate movement mechanism composed of; a member rotatable about a fulcrum; another member rotatable about the same fulcrum; mechanism for bringing said members into a constant position relatively to each other; and a master wheel operated by said first named member. 125
12. In a calculating machine the combination of: a set of digital pins; a constant aggregate movement mechanism cooperating with any of said pins, said mechanism being composed of; a member rotatable about a fulcrum; another member rotatable about the same fulcrum; a third member connected to said members and rotatable about another fulcrum; mechanism for bringing the two fulcrums into collinearity; and a master wheel operated by said first named member. 130
13. In a calculating machine the combination of: a set of digital pins; a constant aggregate movement mechanism cooperating with any of said pins said mechanism being composed of; a member rotatable about a fixed fulcrum; another member rotatable about the same fixed fulcrum; a third member connected to said members and rotatable about a displaceable fulcrum; mechanism for moving the displaceable fulcrum into collinearity with the fixed fulcrum; and a master wheel operated by said first named member. 135
14. In a calculating machine the combination of: a set of digital pins; a constant ag-

- gregate movement mechanism cooperating with any of said pins; said mechanism being composed of; a member rotatable about a fulcrum; another member rotatable about the same fulcrum; a third member connected to said members and rotatable about another fulcrum; and mechanism for bringing the two fulcrums into collinearity.
15. In a calculating machine the combination of: a set of digital pins; a constant aggregate movement mechanism cooperating with any of said pins; said mechanism being composed of; a member rotatable about a fixed fulcrum; another member rotatable about the same fixed fulcrum; a third member connected to said members and rotatable about a displaceable fulcrum; and mechanism for moving the displaceable fulcrum into collinearity with the fixed fulcrum.
20. 16. In a calculating machine, the combination of a set of carrying gears adapted to move laterally to change the decimal place; a master wheel adapted to insert numbers in said carrying gears seriatim; mechanism for moving said master wheel radially to and from said gears to thus engage and disengage said master wheel and gears; and mechanism rotating the master wheel during each engagement thereof.
30. 17. In a calculating machine, the combination of a set of carrying gears having carrying teeth on the exterior portion thereof and adapted to move laterally to change the decimal place; a master wheel adapted to engage said carrying gears seriatim; and also to be given a digital movement; a set of transfer gears located outside of said carrying gears and mechanism for moving the set of transfer gears radially into engagement with the carrying gears for each digital movement of the master wheel.
18. In a calculating machine, the combination of a set of carrying gears adapted to move laterally to change the decimal place, a set of transfer gears located outside of said carrying gears, a master wheel adapted to engage said carrying gears seriatim and insert numbers therein; and mechanism for moving both the master wheel and transfer gears radially into engagement with the carrying gear for each digital movement of the master wheel.
45. 19. In a calculating machine, the combination of a digit key, a cycle shaft rotating always in the same direction, and means positively connected to said cycle shaft to convert a reciprocation of said digit key into a complete cycle of movement of said cycle shaft.
50. 20. In a calculating machine, the combination of a manually reciprocable digital member, a cycle shaft rotatable always in the same direction, and means positively linked to said cycle shaft to convert recipro-
- cation of said digital member into a complete revolution of said cycle shaft.
21. In a calculating machine, the combination of a set of digit keys occupying a normal position and adapted to be displaced therefrom, a universal member adapted to be reciprocated by any of said digit keys, means for locking said universal member to any of said digit keys when said digit key is in a displaced position and for unlocking said universal member from said digit key when said digit key is in its normal position; a cycle body, and a linkage connecting said universal member and said cycle body to insure a revolution of said cycle body corresponding to each reciprocation of said universal member.
22. In a calculating machine, the combination of a universal member, a set of digital members occupying a normal position and adapted to be displaced therefrom to thereby reciprocate said universal member; mechanism for locking any of said digital members and said universal member together during the displacement of said digital member, a cycle shaft, a crank on said cycle shaft, and a link connecting said universal member to said crank, whereby a reciprocation of said universal member results in a complete revolution of said cycle shaft.
23. In a calculating machine, the combination of a universal member, a set of digital members, each occupying a normal position and adapted to be displaced therefrom to thereby displace said universal member, mechanism for locking said universal member to its displaced digital member while said universal member is displaced, a cycle shaft, a crank on said cycle shaft, a link connecting said universal member to said crank, and means operating independent of said link to throw said cycle shaft over its dead points whereby a reciprocation of any of said digit keys results in a complete rotation of said cycle shaft.
24. In a calculating machine, the combination of a set of manually reciprocatable digital members, a universal member adapted to be actuated by any of said digit members, a cycle shaft, a linkage connecting said cycle shaft with said universal member, whereby said cycle member is rotated upon each reciprocation of said universal member, and a mechanism for preventing the reverse rotation of said cycle shaft.
25. In a calculating machine, the combination of a set of manually reciprocatable digital members, a universal member adapted to be actuated by any of said digit members, a cycle shaft, a linkage connecting said cycle shaft with said universal member, whereby said cycle member is rotated upon each reciprocation of said universal mem-

ber, and a pawl and ratchet mechanism to prevent reverse rotation of said cycle shaft.

26. In a calculating machine, the combination of a set of totalizer carrying wheels, a plurality of aligners for said wheels, said aligners being capable of independent motion, whereby one aligner may be moved without disturbing any other aligner, and mechanism for operating the aligners successively to thereby align the lower carrying wheel of the totalizer first and the higher carrying wheel of the totalizer next.

27. In a calculating machine, the combination of a set of digit keys, a universal member operable by any of said keys, a constant aggregate motion linkage operatively connected to said universal member and means brought into operation on the actuation of any of said keys to locate said linkage in a position determined by any of said keys.

28. In a calculating machine, the combination of a set of digit keys, a universal member operable by any of said keys, a constant aggregate motion linkage operatively connected to said universal member, a master wheel adapted to be operatively connected to said linkage, and means brought into operation on the actuation of any of said keys to locate said linkage and master wheel in a position determined by the actuated key.

29. In a calculating machine the combination of, a set of digit keys, a totalizer, a master mechanism therefor, and a constant aggregate motion linkage connecting said master mechanism to said digit keys, and thereby determining the motion of said master mechanism upon operation of said digit keys.

30. In a calculating machine, the combination of, a set of digit keys, a totalizer, a master wheel adapted to insert numbers therein seriatim, and a constant aggregate motion linkage connecting said master wheel to said digit keys, and thereby determining the motion of said master wheel upon operation of said digit keys.

31. In a calculating machine, the combination of a set of digit keys, a totalizer, master mechanism therefor, a constant aggregate motion linkage operative on said master mechanism to give the same a differential movement, operating means for said linkage adapted to be engaged by any of said keys, and means for preventing two of said keys simultaneously engaging said operating means.

32. In a calculating machine, the combination of a set of numeral keys, a rotatable cycle shaft, a universal member adapted to be moved by any of said keys, and a linkage connecting said universal member and said cycle shaft whereby a reciprocation of said universal member is transformed into a complete cycle of said cycle shaft.

33. In a calculating machine, the combina-

tion of a set of numeral keys, a cycle shaft rotatable always in the same direction, a universal member adapted to be moved by any of said keys, and a linkage connecting said universal member and said cycle shaft whereby a reciprocation of said universal member is transformed into a complete cycle of said cycle shaft.

34. In a calculating machine, the combination of a set of numeral keys, a cycle shaft rotatable always in the same direction, a universal member adapted to be moved by any of said keys, and a linkage connecting said universal member and said cycle shaft whereby a reciprocation of said universal member is transformed into a complete revolution of said cycle shaft.

35. In a calculating machine, the combination of a set of numeral keys, a universal member adapted to be reciprocated upon the operation of any said numeral keys, a cycle shaft, a crank and link connecting said cycle shaft to said universal member, and mechanism to rotate said cycle shaft past the dead center positions of said crank and link mechanism.

36. In a calculating machine, the combination of a set of digit keys, a totalizer, master mechanism therefor, a constant aggregate motion linkage operative on said master mechanism to give the same a differential motion, operating means for said linkage adapted to be engaged by any of said keys, and a cramp room mechanism adapted to prevent two of said keys from simultaneously engaging said operating means.

37. In a calculating machine the combination of a set of carrying gears adapted to move laterally to change the decimal place, a set of transfer gears, a master wheel and mechanism for moving both the master wheel and the transfer gears radially into engagement with the carrying gears.

38. In a calculating machine, the combination of a set of carrying wheels, a set of numeral keys, a master wheel, connections between said numeral keys and said master wheel whereby the actuation of any of said keys operates the master wheel a differential amount, a set of transfer gears laterally fixed relative to said master wheel, said carrying wheels being relatively movable to said master wheel and set of transfer gears, a plurality of aligners adapted to engage and align said transfer gears, and means for operating said aligners successively to thereby align a transfer gear of lower order prior to aligning a transfer gear of higher order.

39. In a calculating machine, the combination of a master wheel, a set of totalizer carrying wheels relatively movable thereto, a set of transfer gears, a set of aligners for said transfer gears, a common support for said master wheel, transfer gears and align-

- ers, whereby the same are laterally fixed relative to each other, means to differentially rotate said master wheel on the operation of any of said keys, and means to successively operate said aligners subsequent to said differential rotation of said master wheel whereby said master wheel is first differentially rotated and the transfer gear adjacent to said master wheel is aligned prior to the alignment of a transfer gear of higher order.
40. In a calculating machine, the combination of a set of totalizer carrying wheels, a common locking bar for said wheels, a master wheel, a set of keys, a differential mechanism controlled by said keys and operative on said master wheel whereby the actuation of any of said keys will rotate said master wheel a differential amount, and a master dog operative upon said totalizer locking bar; the cycle being such that a depression of any of said numeral keys first operates said master dog and rotates said master wheel a differential amount, then restores said master dog to its normal position subsequent to the differential rotation of the master wheel.
41. In a calculating machine, the combination of a set of numeral keys, a master wheel, a differential mechanism connecting said master wheel and said numeral keys whereby the actuation of any of said numeral keys rotates said master wheel a differential amount, a totalizer adapted to move relatively to said master wheel and have numbers inserted therein seriatim by said master wheel, a universal locking bar in said totalizer adapted to normally lock a plurality of said totalizer gears, a master dog adapted to engage said universal locking bar, a set of transfer gears laterally fixed with reference to said master wheel and adapted to form a counting chain extending from the left of said master wheel to the totalizer gears of higher orders, a set of aligners for said transfer gears, and mechanism connecting said numeral keys, master dog, master wheel and aligners, such that the actuation of any numeral key will first operate said master dog to unlock said universal locking bar, and rotate said master wheel a differential amount, then successively operate said aligners to align said transfer gears, and then restore said master dog and the then connected locking bar to its normal position prior to the engagement of said master wheel with a totalizer gear of lower order.
42. In a calculating machine, the combination of a set of totalizer carrying wheels, a set of transfer gears in mesh therewith, a plurality of aligners for said transfer gears, said aligners being capable of independent motion, whereby one aligner may be moved without moving a second aligner, and mechanism for operating said aligners successively to align thereby the lower transfer gear and its then associated carrying wheel prior to the alignment of a transfer gear of higher order.
43. In a calculating machine, the combination of a set of digit keys, a set of totalizer carrying wheels, a set of transfer wheels in mesh therewith, a plurality of aligners for said transfer gears, and mechanism controlled by said digit keys for operating said aligners successively to thereby align the lower transfer gear and its then associated totalizer carrying wheel prior to the alignment of the transfer gear of higher order.
44. In a calculating machine, the combination of a set of digit keys, a set of totalizer carrying wheels, a lock for said carrying wheels held in a normal position by a spring, a set of transfer gears in mesh with said carrying wheels, a plurality of aligners for aligning said transfer gears subsequent to the actuation of said gears by any of said carrying wheels, and mechanism controlled by any of said digit keys for operating said lock and said aligners successively and permitting said spring to restore said lock to its normal position.
45. In a calculating machine, the combination of a set of totalizer carrying wheels, a set of keys adapted to operate said wheels at certain times, a plurality of aligners for said wheels and mechanism controlled by said keys for operating said aligners successively to thereby align the lower carrying wheels of the totalizer first and the higher next.
46. In a calculating machine, the combination of a set of totalizer carrying wheels, a set of keys, mechanism controlled by said keys to insert numbers in said totalizer carrying wheels, a plurality of aligners for said wheels and mechanism brought into action subsequent to the insertion of a number into said wheels and governed by said numeral keys for operating said aligners successively to thereby align said totalizer carrying wheels successively from lower to higher order.
47. In a computing machine, the combination with numeral keys, computing wheels, a master wheel, and carry-over mechanism for carrying from lower to higher order, of means for driving said master wheel and carry-over mechanism from said keys, and additional driving connections from said keys to parts of said carry-over mechanism to assist said mechanism when effecting a carrying operation, said additional driving connections operating first on the carrying wheel of lower order prior to operating on the carrying wheel of higher order.
48. In a calculating machine, the combination of a set of totalizer carrying wheels,

- a set of transfer gears in mesh therewith, a master wheel adapted to insert numbers therein, a set of digit keys, differential mechanism connecting said master wheel and said digit keys, whereby the operation of any of said digit keys rotates said master wheel a differential amount, a plurality of aligners for said transfer gears, and mechanism for operating said aligners successively upon the operation of any of said digit keys to align thereby the lower transfer gear and its then associated totalizer carrying wheel prior to the alignment of a transfer gear of higher order.
5. 49. In a calculating machine, the combination of a set of totalizer carrying wheels, a master wheel adapted to insert numbers therein, a set of digit keys, differential mechanism connecting said digit keys with said master wheel, whereby the operation of any of said digit keys rotates said master wheel a differential amount, a plurality of aligners for said totalizer carrying wheels and mechanism for operating said aligners successively to thereby align the lower carrying wheels of the totalizer first and the higher next.
10. 50. In a calculating machine, the combination with a totalizer and a master wheel, one travelling with relation to the other and the latter normally out of the path of the former, of means for operating said master wheel but normally out of gear therewith, and means for simultaneously moving said master wheel into gear with said totalizer and into gear with said operating means.
15. 51. In a calculating machine, the combination with a totalizer and a master wheel, one travelling with relation to the other and the latter normally out of the path of the former, of a reciprocating rack for operating said master wheel differentially, and shifting means for bringing said master wheel into gear with said totalizer and into gear with said rack preliminary to an operation of said master wheel by said rack.
20. 52. In a calculating machine, the combination with a totalizer and a master wheel, one travelling with relation to the other and the latter normally out of the path of the former, of a shifting frame in which said master wheel is mounted, a pinion in said frame and geared to said master wheel, a differentially movable rack normally out of mesh with said pinion, and means for shifting said frame thereby to bring said master wheel into gear with said totalizer and said pinion into mesh with said rack.
25. 53. In a calculating machine, the combination with one or more totalizers and a plurality of master wheels travelling one relatively to the other and the latter normally out of the path of the former, of a pinion in gear with all said master wheels, a differential rack for operating said pinion, and means for simultaneously shifting said master wheels into position to gear with said totalizer or totalizers and for shifting said pinion into gear with said rack preliminary to an operation of said rack, pinion and master wheels.
30. 54. In a calculating machine, the combination with a registering device, of a constant aggregate motion mechanism for operating said registering device, means movable to an invariable extent for operating said constant aggregate motion mechanism, a set of keys, and a universal member for operating said invariably movable means and to which an operated key becomes positively coupled.
35. 55. In a calculating machine, the combination of a set of keys, a universal bar for said keys, means for coupling an operated key to said universal bar, means for insuring a full stroke to said universal bar, a constant aggregate motion mechanism operated by said universal bar, an actuator operated by one of the members of said constant aggregate motion mechanism, and a registering element operated by said actuator.
40. 56. In a calculating machine, the combination of a set of numeral keys, a cycle shaft operated by said keys, a register, an actuator for said register, a differential rack for operating said actuator, means operated by said cycle shaft for moving said actuator into and out of gear with said register and with said differential rack, and means operated by said cycle shaft for operating said differential rack while it is in gear with said actuator.
45. In witness whereof, I have hereunto signed my name, this 6th day of September 1912.
- HYMAN ELI GOLDBERG.
